UNITED STATES PATENT OFFICE.

GEORGE E. STARBOARD, OF ELMHURST, ILLINOIS, AND GEORGE M. FOX, OF CUT BANK, MONTANA.

CAR-COUPING.

No. 876,500.

Specification of Letters Patent.

Patented Jan. 14, 1908.

Application filed February 4, 1907. Serial No. 355,679.

To all whom it may concern:

Be it known that we, GEORGE E. STAR-
BIRD and GEORGE M. FOX, citizens of the
United States, residing, respectively, at
5 Elmhurst, in the county of Dupage and
State of Illinois, and at Cut Bank, in the
county of Teton and State of Montana, have
invented certain new and useful Improve-
ments in Car-Couplings; and we do declare
10 the following to be a full, clear, and exact
description of the invention, such as will
enable others skilled in the art to which it
appertains to make and use the same.

Our invention relates to improvements
15 in car couplings of the Janney type, par-
ticularly with reference to the construction
of the knuckle and of improved means for re-
leasing the knuckle and causing the same to
swing to open position when uncoupling the
20 cars, and it consists in the construction,
combination, and arrangement of devices
hereinafter described and claimed.

In the accompanying drawings, Figure 1
25 is a side elevation of our improved car coup-
ling, showing a portion of the car to which it
is attached; Fig. 2 is a horizontal sectional
view of the same, taken on the plane in-
dicated by the line *a—a* of Fig. 1; Fig. 3 is
30 a vertical sectional view of the same. Fig.
4 represents an end elevation of this im-
proved coupling applied.

The draw bar is composed of an upper sec-
tion 1 and a lower section 2, bolted or other-
wise suitably secured together, and provided
35 at their rear ends, on their upper and lower
sides, respectively, with shoulders 3 to en-
gage a plate 4 which connects the draft
beams 5 and a shoulder 6. A lock block 7 is
40 pivoted near its rear end, as at 8, in a longi-
tudinal opening 9 in the draw head. Said
lock block is provided on one side, near its
free end, with a notch 10, and the lower
45 section of the draw bar is formed with a
shoulder 11 to engage said notch when the
lock block is in its lowered, normal position
and assist the pivot 8 to withstand longitu-
dinal stress on the lock block. Said lock
50 block is provided on its opposite side near
its free end, with a shoulder 12, and a notch
13 immediately in rear of said shoulder.
The knuckle 14 is provided with a rearwardly
extending arm 15 to enter a recess 16 in the
inner side of the jaw 17. Said arm has a
notch 18 to receive the shoulder 12 of the

lock block and a shoulder 19 to enter the 55
notch 13 of said lock block. The knuckle is
pivotally connected to the said jaw by the
usual pin 20, and when the arm of the knuc-
kle is engaged with the block, when the lat-
ter is lowered and the knuckle closed said 60
lock block partially relieves the pin 20 of
draft stress, as will be understood. The face
21 of the knuckle is coextensive in height
with the jaw 17 of the knuckle, that is to say,
it is formed at its upper and lower sides with 65
extensions 22, concaved on their inner sides,
to bear on the lugs 23 which project for-
wardly from the jaw 17 and receive the
pivot pin 20. This greatly strengthens the
construction, both of the knuckles and the 70
draw head and adds very greatly to the du-
rability thereof. At the rear end of the lock
block is a lever arm 24 which extends down-
wardly therefrom and projects through an
opening 25 in the lower section of the draw 75
bar.

In the lower section of the drawbar is a
recess 26, which communicates with the re-
cess 16 and in which operates the crank arm
27 of a rock shaft 28 which is vertically dis-
posed, and journaled in an opening in the 80
lower portion of the draw head. To the
lower end of said rock shaft is secured a rear-
wardly extending tappet arm 29, which is
extended downwardly. Said tappet arm 85
has a forwardly extending portion 30, con-
nected by a slack chain 31 to the draw head,
to prevent loss of the tappet arm should it
become casually detached from the rock
shaft and the latter become broken. 90

Under the end of the car is a revoluble and
longitudinally movable operating shaft 32
which is disposed transversely with respect
to the car, extends to one side thereof and is
mounted on suitable bearings in hangers or 95
other suitable devices 33, 34. The inner
portion of said shaft, where it travels through
the bearings 34, is angular and on said angu-
lar portion is loosely mounted a lock-block-
operating arm 35, which has an angular 100
opening to receive the angular portion of said
shaft, so that the latter is free to move longi-
tudinally independently of the said arm, and
said arm is caused to turn with said shaft.
The bearing 33 has a notch 36, and the oper-
ating shaft has a key or spline 37 to coact
with said notch to lock the said shaft against
rotation. The arm 35 is connected by a 105

chain 38 to the lever arm 24 of the lock block. The operating shaft is also provided with a tappet arm 39 which is fixed thereto.

The operation of our invention is as follows:—In order to uncouple, the operating shaft is partly turned, which may be done by a man stationed at one side of the car, out of the way, to cause the arm 35 to draw upon the chain 38 and the lever arm 24 and hence cause the free end of the lock block to be raised, so as to disengage the arm of the knuckle. Such partial rotary movement of the operating shaft brings its key or spline 37 into alinement with the notch 36 of the bearing 33, and the said shaft is then moved longitudinally; inwardly, to cause its tappet arm to engage that of the crank shaft, and partly turn said crank shaft so as to cause its crank arm to turn, and by so doing, also cause the knuckle to be positively turned to open or uncoupled position. The length of the spline is such that it remains in the notch 36 when the operating shaft is thus moved inwardly and coacts with said notch to lock the shaft against rotation and hence to keep the lock block in elevated position until the knuckle has been turned to open position. The operating shaft must then be moved outwardly to withdraw its tappet arm from that of the knuckle-operating rock shaft, and to withdraw its spline from the notch 36, and permit the arm 39 to drop and the arm 35 to rise, to slacken the chain 38 and permit the

free end of the lock block to drop on the arm of the knuckle, ready to reengage said arm 35 and lock the knuckle when the latter is automatically turned to coupling or closed position, as will be understood.

Having thus described our invention, what we claim as new and desire to secure by Letters Patent is:—

In a car coupling of the Janney type, in combination with the drawhead and the pivoted knuckle having the arm, a lock block in the drawhead mounted for vertical pivotal movement, a revoluble element to open the knuckle and having a tappet arm, and a revoluble and longitudinally movable operating element, having a connection with the lock block to operate the latter and also having a tappet arm to coact with that of the revoluble knuckle-opening element.

In testimony whereof we have hereunto set our hands, each in the presence of two subscribing witnesses.
